LADY'S SHOE

Akiyasu Ishida, Yutokuso, 1 Chyome 35 Banchi-11,
Nishi-Machi, Kawaguchi-shi, Saitama-ken, Japan

Filed Jan. 27, 1964, Ser. No. 78,379

Claims priority, application Japan Sept. 9, 1963

Term of patent 14 years

(Cl. D7—5)

FIG. 3

FIG. 1

FIG. 2

FIG. 1 is a side elevation of a lady's shoe, showing my new design;

FIG. 2 is a bottom plan view thereof;

FIG. 3 is a rear elevation thereof.

The essential feature of my design resides in the heel portion as shown in full lines consisting primarily of a narrow generally cylindrical shank having an opening at the top substantially as shown.

I claim:

The ornamental design for a lady's shoe, as shown and described.
